UNITED STATES PATENT OFFICE.

CLEMENT JUNGERS, OF STREATOR, ILLINOIS.

DESIGN FOR SHEET-GLASS.

40,845.

Specification for Design.

Patented Aug. 30, 1910.

Application filed February 7, 1910. Serial No. 542,657. Term of patent 14 years.

To all whom it may concern:

Be it known that I, CLEMENT JUNGERS, a citizen of the United States, residing at Streator, in the county of LaSalle and State of Illinois, have invented a new, original, and ornamental Design for Sheet-Glass, of which the following is a specification, reference being had to the accompanying drawing, forming a part thereof.

The figure shown is a face or plan view of a section of glass showing my new design.

The design in question is characterized in that it has a series of star shaped whirls

so spaced apart that their tips approach closely to each other and between these whirls are sprays of holly, these sprays being desirably upon a stippled or roughened background.

I claim—

The ornamental design for sheet glass as shown and described.

CLEMENT JUNGERS.
